ATTORNEY.

UNITED STATES PATENT OFFICE.

WILLIAM H. THOMMEN, OF PLYMOUTH, WISCONSIN.

DESIGN FOR A PHONOGRAPH.

59,989.

Specification for Design.

Patented Dec. 13, 1921.

Application filed March 25, 1921. Serial No. 455,655. Term of patent 14 years.

To all whom it may concern:

Be it known that I, WILLIAM H. THOMMEN, a citizen of the United States, residing at Plymouth, in the county of Sheboygan and State of Wisconsin, have invented a new, original, and ornamental design for phonographs, and especially for the sound-wave-amplifying structure of sound-reproducing machines irrespective of the specific form of cabinets or propelling-motors employed, of which the following is a specification, reference being had to the accompanying drawing, forming a part thereof.

Figure 1 is a perspective view of a phonograph, embodying a sound wave amplifier constructed in accordance with my new design, showing the sound modifying lid in closed position.

Fig. 2 is an enlarged top view of a phonograph embodying a sound wave amplifier constructed in accordance with my new design, showing the sound modifying lid fully opened.

Fig. 3 is an enlarged bottom view of a phonograph embodying a sound wave amplifier constructed in accordance with my new design.

I claim:

The ornamental design for a phonograph, substantially as shown and described.

In testimony whereof, the signature of the inventor is affixed hereto.

WILLIAM H. THOMMEN.
